[57] CLAIM

The ornamental design for a lighting system control console, substantially as shown and described.

DESCRIPTION

FIG. 1 is a perspective view of the console according to the present invention;

FIG. 2 is a bottom plan view thereof;

FIG. 3 is a rear perspective view thereof;

FIG. 4 is a bottom plan view of the monitor mounted on the console; and

FIG. 5 is a side elevational view thereof, the other side being a mirror image.

Fig. 1.

Fig. 3.

Fig. 4.

Fig. 5.
